FUEL BURNER CONTROLLER

Paul F. Shivers, Minneapolis, Minn., assignor to
 Minneapolis-Honeywell Regulator Company,
 Minneapolis, Minn., a corporation of Delaware

Application October 22, 1948, Serial No. 55,962

13 Claims. (Cl. 175—375)

1

This invention relates to improvements in fuel burner controllers of the type which provides for the initiation of the supply of fuel to a furnace and the substantially simultaneous ignition thereof, upon a demand for heat output by the furnace. A furnace controller of this type is illustrated and described in the Sparrow et al. patent, No. 2,420,105, dated May 6, 1947. This invention differs from the device shown in the above mentioned patent in that it provides for shutting off the igniting means upon proper or satisfactory ignition of the fuel. In addition to this, the present invention provides a single manual controller which will simultaneously reset a safety switch and place various elements of the device in proper relationship for a desired timed sequence of operation, after there has been a safety shutdown of the furnace by the control device, or after a long summer shutdown of the furnace, during which time the elements may have gotten out of "step" for one reason or another.

In controllers or devices of this type, it is common practice to provide a slip-friction mechanism responsive to stack temperatures to establish a holding circuit for the relay in the event ignition takes place and to provide a safety shutoff switch, in series with the fuel controller, which will cut off the fuel supply in the event that ignition does not take place. The well known function performed by the slip-friction mechanism of control devices has its drawbacks in that once in a great while the clutch of the slip-friction means fails to grip its actuator as soon as it should and, therefore, gets out of "step," requiring the manual resetting thereof to put it back in "step." While the average householder may not appreciate the necessity for placing the controller in step, they usually know or have been told about the means for resetting the controller after a safety shutdown, which probably occurs more often than the device gets out of step. It is with this problem of providing simpler means for a householder to put all of the elements of the controller and the furnace back into proper operation, should the ignition means fail to cutoff, or the slip-friction means get out of step, or there is safety shutdown, that this invention is primarily concerned.

One of the objects of this invention is to provide a fuel burner controller having a single manually actuatable member that will actuate an igniter switch to its open position, reset a safety switch and place a slip friction mechanism in "step" upon a single actuation of the member.

Another object of the invention is to provide a control device for a fuel burning furnace that has

5 a simple and inexpensive mechanism for cutting off the igniter after ignition has taken place and may be manually actuated to shut off the igniter in the event that automatic means for shutting it off fails to operate.

10 A further object of the invention is to provide in a furnace controller a simple but reliable means for resetting a safety switch and for placing a slip-friction mechanism in "step."

15 Still another object of the invention is to supply an ignition switch that has means to cause a quick breaking of its ignition contacts.

Other objects and advantages of the invention will become apparent upon reading the following 20 detailed description thereof in conjunction with the appended drawings in which:

Figure 1 is a side elevational view of the controller with portions thereof broken away;

Figure 2 is a bottom view of the controller with 25 portions thereof broken away;

Figure 3 is a schematic showing of elements of the controller and the control system of which they form a part;

Figure 4 is an elevational view of one of two 30 switch units of the controller;

Figure 5 is a plan view of the relay of the controller with portions thereof broken away;

Figure 6 is a side elevational view of the relay with portions thereof broken away;

35 Figure 7 is a side elevational view of the safety switch and the manual controller or reset means; and

Figure 8 is a plan view of the safety switch and manual controller or reset means.

40 In the drawings, wherein like reference numerals indicate the same parts, the reference numeral 11 designates the panel upon which the various mechanisms of the controller or control device are mounted and secured. Mounted on the panel

45 11 by bolts or other suitable fastening means are a conventional step-down transformer 12, a safety cutout switch 13, a relay 14, and a switching mechanism housing 15. Positioned on the opposite side of the panel from the switching mechanism housing is a tubular member 16 carrying a mounting flange 17 which is slidably adjustable over the intermediate portion thereof. The flange has spaced openings 18 to provide for the bolting of the controller to a stack (not shown) of a furnace (not shown). The tube 16 is secured to the panel 11 by bent over ears 19 extending through a backing plate 11a and/or openings in the panel. The backing plate 11a is secured to the panel 11 either by welding or by any other suitable means. Terminal blocks 19 and 20 are suitably secured to

inwardly bent ears on the side walls of the panel 11 to facilitate connection of the controller to other elements of the control system.

As can best be seen in Figures 5 and 6 of the drawing, the relay 14 comprises a relay coil 21 mounted on a core member 22 of general U-shape. An armature member 23, having a bearing plate 24 secured thereto by means of bolts 25, is pivotally mounted on a pronged pivot 26 suitably secured to one leg of the relay core 22. A tension spring 27 extends between the outer end of the bearing plate 24 and the outer end of a laterally projecting arm 26a of the pivot 26, to normally urge the armature away from the magnet. A plurality of parallel flexible contact arms 28, 28a, 28b, 28c and 28d (see Figures 3 and 6) are clamped to the armature 23 between two insulation members 29 and 30 (see Figures 3 and 6). Arms 28b, 28c and 28d are electrically connected. These flexible contact arms are adapted to engage fixed contact arms 31, 31a, 31b, 31c and 31d (see Figure 3) clamped between an insulation block 32 and a latch unit 33 by means of a bolt 34 screw-threaded into the other leg of the U-shaped core member of the relay as shown in Figure 6.

The latch unit 33 is formed of two longitudinally grooved blocks 35 and 36 of insulation material which, when clamped together, provide an open-ended guide-way 37 and 37a. The block 35 has a transverse opening 38 near one end thereof and a notch 39 at the adjacent end, for reasons to be described hereinafter. The block 36 has transverse openings 40, 41 and 42 for purposes to be described below. An arm 36a extends laterally from the main portion of the block 36 to provide a protective cover and stop for the flexible contact arms. The longitudinal groove 37a in the block 36 is laterally widened to provide shoulders 43 (see Figure 5) to provide abutment shoulders for a latch member 44 now to be described. Said latch member having a general A-shape with outwardly extending feet 45 which are adapted to move into and out of engagement with the shoulders 43, is slidably mounted in the longitudinal grooves 37 and 37a under the bias of a spring 46. The spring, due to its position in the recesses of the block 36 (see Figure 6), normally biases the latch member 44 toward the block 35 and the feet 45 toward the shoulders 43. An opening 46 in the latch member is notched out at 47 the width of the adjacent main portion of the armature 23 while the main opening 46 is slightly wider than a head 23a on the outer end of the armature 23 forming a shoulder that is to be engaged by said head in the normal inoperative position of the relay. The latch member 44 fits sufficiently loose in the longitudinal groove 37a that it may be deflected laterally or longitudinally of the armature so as to move out of alignment with the head 23a, thus enabling the narrow portion of the armature to slide down into recess 47 of the latch member for reasons to be described hereinafter. A cross piece 48 of insulation material spans another recess 49 communicating with the opening 46 and is positioned to normally engage an extension on the flexible contact arm 28a when the relay is in its deenergized condition. The outer end of the latch member 44 is bent laterally to form a cam surface 44a to cooperate with another cam element of the control device to effect the lateral shifting of the latch member out of alignment with the head 23a. It will thus be seen that energization of the relay will cause

movement of the armature about the pivot member 26 in a direction to bring the flexible contact arms into engagement with the fixed contact arms and to move the latch member 44, through head 23a, to its innermost position. The elements of the relay will stay in this position until said cam element deflects the cam surface 44a and consequently the latch member 44 out of alignment with the head 23a, thus permitting the spring 46 to slide the latch member 44 longitudinally in the groove 37a. This will cause the bridging member 48 to snap the flexible contact arm 28a out of engagement with fixed contact 31a and to bring feet 45 into engagement with the shoulders 43, thus limiting the outward movement of the latch member.

Referring now to Figures 1, 2 and 3 of the drawings, the switching mechanism in the housing 15 is positioned directly above the relay and comprises elements which perform the same functions as the switching mechanism disclosed in the above mentioned Sparrow et al. patent. A lazy W-shaped temperature sensing element 50 of well known construction is secured at one of its ends to the inner end of the tube 16 by means of a bolt while the other end thereof is secured by a bolt to a connecting rod 51 which in turn is connected through a spring type of universal joint 52 (see Figure 3) to a control rod 53. With the exception of a cam deflector member 54 extending downwardly below an adjustable plate 55 (Figure 1) and adjustably secured to a switch actuating clutch plate 56 (Figure 3) through a mounting bracket 56 (Figure 1), the details of the switching mechanism form no portion of this invention. However, to enable one skilled in the art to practice this invention, the mechanism will be more or less schematically described with reference to Figure 3 of the drawing. A wall 57 of the switching mechanism housing supports two "cold" contacts 58 and 59 which are of equal length and a third "cold" contact 60 which is slightly shorter than the contacts 58 and 59. On the other side of the wall 57 are two "hot" contacts 61 and 62 which are of equal length. Two other walls 63 and 64 of the mechanism housing are spaced on opposite sides of the wall 57 and slidably carry bearing stems 65 and 66, respectively, of bridging switch units 67 and 68 having body portions made of insulation material. The unit 68 has a laterally extending cylindrical portion 69 telescopically receiving a laterally extending stem 70 from the switch unit 67. A spring 71 surrounds the members 69 and 70 and extends through a large opening 57a in the wall 57 to normally urge the two switch units apart. Each of the switch units carries a serpentine-shaped flexible contact arm member 72 and 72a (see Figure 4) which is secured to the body portion by means of rivets 73 leaving three flexible contact arms 74, 75 and 76 and 74a, 75a and 76a, respectively. A clutch plate 77 is slidably mounted on the control rod 53 and bears at its outer end against the end of stem 66, to urge the switching unit 68 toward the left when the control rod 53 moves toward the left, upon heat developing in the stack of the furnace. The unit can continue moving toward the left even after contacts 74 and 76 engage fixed contacts 62 and 61 respectively, due to the flexing of the contacts 74 and 76, until the clutch plate 77 engages an adjustable stop 78. Thereafter, the control rod 53 will slip through the clutch plate 77 in a well known manner. The spring 71 causes the clutch plate 77 to follow the movement of the control rod 53 toward the

right when the stack temperature cools down. It will move toward the right until the clutch plate 77 engages an adjustable or fixed wall 79, whereupon the rod 53 will slip through plate 77. A clutch plate 80, which carries a cam-shaped abutment 54 for cooperation with the cam 44a on the relay latch member 44, operates in the reverse direction with respect to the cam plate 77. In other words, it is moved toward the right by the same movement of the rod 53 and is urged toward the left by the spring 71 as the rod 53 moves toward the left. It is limited in its leftward movement by an adjustable stop 81 and in its movement toward the right by adjustable stop 82. With the main exception that the switching mechanism is shown below the control rod 53, the relay side of said control rod, whereas in fact it is on the other side of said control rod (see Figure 1), the elements of the switching mechanism are shown in the positions they would assume when the relay is deenergized and the stack of the furnace has cooled down to its low or no fire temperature.

Referring now to Figures 7 and 8, the means for manually actuating the control rod 53 outwardly so as to bring cam 54 into engagement with cam 44, for the purpose described above and for moving the control rod 53 sufficiently far through the clutch plate 80 so as to assure the closing of the cold contacts 74a, 75a and 76a on contacts 58, 60 and 59 respectively, comprises a pivoted lever 83 secured by a pivot 84 to a frame 85 of the safety cutout switch 13. A cam portion 83a of the pivoted lever is engaged by a stud 86 extending laterally from a manually operable lever 87 pivoted to the frame 85 at 88. An insulation disk 89 is mounted on the outer end of one leg of an L-shaped pivoted lever 90 and engages the free end of a flexible contact arm 91 biased toward said disk. A second insulation disk 92 is mounted on the pivoted lever 87 in transverse alignment with but spaced from a second flexible contact arm 93 normally biased against the contact arm 91. The end of the other leg of the L-shaped lever 90 is positioned to bear against the free end of a bimetallic arm 94 of a heat motor to be presently described. The arms 90a and 94 are so positioned that a predetermined heating of the bimetallic arm 94 will cause movement thereof out from under the arm 90a, permitting said arm 90a to drop or move inwardly thereof under the bias of the resilient or flexible contact arm 91. The contact arm 93 will tend to follow the contact arm 91 but comes into engagement with the insulation disk 92 to limit the following movement, thus breaking the contacts between the arms 91 and 93. A conventional resistance heater 95 is positioned between and riveted to an end of the bimetal 94 and an end of a cooperating bimetal 94a, each of which moves the outer end of the bimetal 94 outwardly from under the free end of arm 90a upon a rise in temperature thereof. The other end of the bimetal arm 94a is riveted through a spacer 96 to a third bimetallic arm 97 which serves as an ambient temperature compensating unit in that it carries the bimetallic arms 94a and 94 in the opposite direction inwardly of the arm 90a upon a rise in temperature, in a manner well known in the art. The other end of the bimetallic arm 97 is riveted to a pivoted lever 98. A spring 99 positioned between ears 98a and 85c on the lever 98 and frame 85, respectively, and a bolt 100 passing through said ears and said spring, provides means for adjusting the angular relationship of the

lever 98 and thus the calibration of the heat motor element, to determine the temperature at which bimetal 94 moves out from under the arm 90a. This determines how long it will take for the contacts 91 and 93 to separate after the heat motor has become energized for a reason to be described presently. The lever 98 is held in its pivoted position by means of a clip spring 101 riveted to the frame 85. The ends 102 and 103 of the heater resistor are connected to conductor bars 104 and 105, respectively. These conductor bars, as well as the fixed ends of the contact arms 91 and 93, are bent in two planes and extend through the base 85a of the frame 85, with terminal ends 91a, 93a, 104a and 105 extending outwardly beyond said base. The contact arms and bars are clamped to said base 85a between insulation blocks 106 and 107 by means of a bolt 108 and nut 109. They are so positioned with respect to each other that they are electrically separated.

The control rod 53 passes through the outer free end of the lever 83 and carries at its outer end a bearing plate 53a held thereon by a split washer 53b resting in an angular groove in the rod 53. It is thus seen that if the switch were in its open condition and the manually actuatable arm 87 were rotated clockwise about its pivot, the insulation disk 92 would first move contact arm 93 further out of engagement with 91 before a lug 87a on lever 87 could engage 90a, to rotate insulation disk 89 clockwise to cause movement of the contact arm 91 and the end of arm 90a to the position shown in Figure 8 of the drawing. As the lever 87 moves clockwise, the cam 86 will ride outwardly on cam 83a to cause the lever 83 to move counterclockwise into engagement with abutment 53a and to move the control rod 53 toward the left. The control rod 53 is moved sufficiently far to the left to assure the closing of contacts 58—74a, 60—75a and 59—76a upon releasing the lever 87. An abutment 85b limits the outward movement of the lever 83 so as to prevent damaging of the member 50.

The above described controller is adapted to be used with a conventional room thermostat 110 (Figure 3) having two blades 111 and 112 adapted to cooperate with contacts 113 and 114, respectively. The contact 113 is connected through line 115 to one side of the secondary coil of transformer 12. The contact 114 is connected through line 116 to relay contact 31c. The contact arms 111 and 112 are connected through line 117 to contact 31d of the relay. Relay contact arm 28 is connected through the terminal panel 20 to the motor of a fuel feeding means or draft regulator or any other means which regulates the supply of combustion material to the furnace (not shown). The other side of the motor 118 is connected to one high voltage line 119. One side of a conventional ignition means 120 is connected through line 121 and line 118b to line 119. The other side of the ignition means is connected through line 122 to contact member 31a on the relay. The contact 31 of the relay is connected through line 123 to the other line 124 of the high voltage line to complete circuits through the motor and ignition means when the relay is energized closing contacts 28—31 and contacts 28a—31a. The ends of the primary coil of the transformer 12 are connected through lines 125 and 126 to the high voltage lines 119 and 124, respectively. It is to be understood that all of the lines to the room thermostat, the

motor, the ignition means and the high voltage line are made through the terminal panels 19 and 20 in a conventional manner.

The internal wiring of the controller may best be understood by describing it in conjunction with an explanation of the operation of the controller in the system illustrated in Figure 3 and as installed on a furnace. With the controller in proper position on a furnace, with the temperature sensing element 50 within the stack of said furnace, and there being no fire present in the furnace, as well as a satisfied room condition, the elements of the system will be in the positions shown in Figure 3 of the drawing.

Operation

Upon a demand for heat due to the lowering of the room temperature surrounding the thermostat 110, the blade 111 of the room thermostat will come into engagement with fixed contact 113. This will not have any effect on the system or controller as the contacts 28d and 31d are separated. However, as the room cools down still more, contact arm 112 will engage contact 114 and complete a circuit to the relay 14 from the upper side of the transformer secondary through line 115, contact 113, arm 111, arm 112, contact 114, line 116, line 127, contact 60, contact 75a, contact 74a, contact 58, line 128, heater 95, line 105, contact arm 91, contact arm 93, line 129, relay 14 and line 130 to the lower terminal of the transformer secondary coil. Energization of the relay causes movement of contact arms 28, 28a, 28b, 28c, 28d, and the armature 23 and latch 44 to their right hand positions completing the circuits to the fuel feeding motor and the igniter as described above and other circuits to be described presently. After the fuel has ignited and the stack has risen in temperature sufficiently to cause the temperature sensing element 50 to move the control rod 53 toward the left, the clutch plate 77, due to its angular relationship with respect to the rod 53, will grip said rod and move along with it so as to move the contacts 74 and 76 toward the left. Switch unit 67 will move along with the control rod 53 due to the compression of spring 71 between the bodies of the switch units 67 and 68. The switch units are factory calibrated so as to cause contact 75a to separate from "cold" or "recycling" contact 60 before contacts 74 and 76 engage or bridge their cooperating "hot" contacts 62 and 61, respectively.

It will be readily apparent that the calibration could permit the contacts 75a and 60 to separate after the "hot" contacts close, but this would shorten the scavenging or purging period to be described presently. Due to the greater amount of flexing of contact arms 74 and 76 with respect to contact arm 75 and the gap between contacts 61 and 76 and 62 and 74, the contacts 74a and 76a will not break from their cooperating "cold" contacts 58 and 59, respectively, until after the "hot" contacts have closed. While one of two temporary holding circuits completed around contacts 112 and 114 upon energization of the relay, the one completed through contacts 28d-31d and 28c-31c will be broken when contacts 60 and 75a separate with the first increment of movement of the control rod, the second temporary holding circuit through contacts 28d-31d and contacts 28b-31b, line 129 and contacts 59 and 76a will be maintained. The heating of heat motor 95 will continue until the "hot" contacts close shunting out the heater and estab-

lishing a third main holding circuit around the contacts 112 and 114 through switches 28d-31d, 28b-31b, line 129, line 130, contacts 62-74 and contacts 61-76 and line 131 to contact arm 91.

- 5 The shunting out of heater 95 prevents sufficient heating thereof to cause tripping of the safety cutout switch 91-93, which would obviously take place should there be flame failure prior to the closing of the "hot" contacts. The contacts 74a and 76a may be calibrated to separate from contacts 58 and 59 respectively after a small increment of movement of the control rod 53 after the "hot" contacts have closed, it being only important that there be some overlapping of the time 10 that the "hot" and "cold" contacts are closed during the movement of the control rod 53 toward the left. The breaking of these cold contacts breaks the circuit to the heater 95 to permit it to cool off during the operation of the burner. Operation of the cam 54 with respect to cam 44 so as to trip the latch and cause said latch to open the ignition switch 28a-31a is not critical but preferably timed to terminate ignition shortly after contacts 74a-58 and 76a-59 15 have separated, to insure steady initial burning of the fuel during the starting cycle.

Should there be a flame failure after combustion has been established, and while the space or room thermostat 110 is still calling for heat, the temperature sensing unit 50 will start to cool and move the control rod 53 toward the right. As an explosion might result if ignition took place at this time, of the unburned fuel remaining in a gaseous state in the furnace, the controller is calibrated so as to have the switching unit 67 move sufficiently far before it engages adjustable stop 81 as to assure breaking of the hot contacts before the cold contacts make and to allow time for the unburned fuel to pass out of the furnace. 20 The breaking of the "hot" contacts immediately deenergizes the relay 14 and shuts off the supply of fuel to the furnace. Obviously, the length of time that it takes for the "cold" contacts to close following terminal of combustion, may be regulated by varying the distance of adjustable stop 81 with respect to fixed contacts 58 and 59 and 60. Even after contacts 74a and 76a engage contacts 58 and 59, respectively, the controller will not recycle due to the fact that shorter contact 60 controls the starting of the control system, the contact 28b being separate from contact 31b upon deenergization of the relay. This provides an additional purging time for the unburned gases in the furnace and assures safe operation thereof. 25 The length of the purging time may obviously be varied by adjusting the position of stop 81.

Should there be ignition failure prior to the closing of the "hot" contacts, the continued heating of heater 95 will cause the tripping of the safety cutout switch 13. Should there be failure of operation due to the fact that the "cold" contacts fail to make in one of their operating cycles, either one or both of the control units will be put back into operating condition by the simple manipulation of the single manual control 87 in the manner described above. Movement of the lever 87 clockwise pulls the control rod 53 slightly beyond the outermost position which the rod would reach in the normal operation of the controller and will simultaneously move the contact arms 91 and 93 and arm 90a to positions which enable the bimetal 94 to align with arm 90a and to hold all three arms in their operating positions upon releasing the lever 87. Also, unless there is something materially wrong with the clutch 80, the 30 35 40 45 50 55 60 65 70 75 80 85 90 95 100

releasing of the lever 87 will permit the rod 53 to move the "cold" contacts to their closed position.

Except when the safety cutout switch is open, operation of the fuel feeding means is controlled by the room thermostat. That is, the fuel feeding means can start operating only when the room thermostat calls for heat and will stop operating when the room thermostat becomes satisfied. Should it be desirable for any reason to terminate ignition from adjacent the furnace immediately after the relay has become energized, as when the apparatus is being tested and adjusted, it is obvious that operation of the manually operable lever 87 will move the control rod 53 to trip the ignition switch latch.

As it is apparent that the above described controller may have wider use than that disclosed above, and that modifications may be made therein without departing from the spirit of the invention, it is to be understood that the scope of the invention is to be determined solely by the appended claims.

I claim as my invention:

1. A circuit controlling device comprising a relay, a first relay operated switch, a second relay actuated switch, a latch biased to move and to hold said second switch in its open position and having an abutment thereon, an arm on said relay normally in alignment with said abutment for moving said latch away from said second switch upon actuation of said relay in a switch closing direction, a deflector means positioned to contact and disengage said arm from said abutment to permit said latch to open said second switch from its closed position, condition responsive slip friction means for actuating said deflector, a normally closed third switch in series with said relay for deenergizing said relay upon a predetermined condition arising, a stop positioned to limit the movement of said deflector means in its arm actuating direction and a manually operable member for simultaneously resetting said third switch and actuating said slip friction means in a direction to press said deflector means against said stop.

2. A circuit controlling device comprising a relay, a first relay operated switch, a second relay actuated switch, a latch biased to move and to hold said second switch in its open position, means operable by said relay for moving said latch away from said second switch upon actuation of said relay in a switch closing direction to enable said second switch to close, a deflector for disengaging said latch from said means to permit said latch to open said second switch from its closed position, condition responsive slip friction means connected to said means and a manually operable member for actuating said slip friction means in a direction to disengage said means from said latch.

3. A fuel burner controller comprising a switch, a relay, slip-friction means for actuating said switch, a plurality of relay actuated switches, latch means for one of said relay actuated switches positioned to cause closing thereof upon energization of said relay, a relay operated arm positioned to actuate said latch means, a cam on said slip-friction means for engaging and releasing said latch means to cause opening of said one switch at a predetermined condition of said slip-friction means, a normally closed safety switch connected in series with said relay for breaking the circuit thereto upon an unsafe condition arising, and means for simultaneously re-

setting said safety switch and actuating said slip-friction means.

4. A fuel burner controller comprising a plurality of switches, condition responsive slip-friction means for actuating said switches, a relay, a plurality of relay actuated switches, latch means for one of said relay actuated switches biased toward switch open position but movable by said relay to cause closing thereof upon energization of said relay, and a cam on said slip-friction means for engaging and releasing said latch means from said relay to cause opening of said one switch at a predetermined position of said slip-friction means.

5. A fuel burner controller comprising a switch, a relay, condition responsive slip-friction means for actuating said switch, a plurality of relay actuated switches, relay actuated latch means for one of said relay actuated switches positioned to permit closing thereof upon energization of said relay, said latch means being biased toward switch open position, a cam on said slip-friction means for engaging and releasing said latch means from said relay to cause opening of said one switch at a predetermined position of said slip-friction means, a normally closed safety switch connected in series with said relay for breaking the circuit thereto upon an unsafe condition arising, and means for simultaneously resetting said safety switch and actuating said slip-friction means.

6. A fuel burner controller comprising a switch, a relay, condition responsive means for actuating said switch, a plurality of relay actuated switches, resiliently biased relay operable switch engaging latch means for one only of said relay actuated switches positioned to move away from said one switch to permit closing thereof upon energization of said relay, and a cam on said condition responsive means for engaging and releasing said latch means from said relay to cause opening of said one switch at a predetermined position of said condition responsive means.

7. In an ignition and fuel control device, the combination comprising an electromagnet, an armature positioned to be moved by said electromagnet, an abutment shoulder on said armature, fixed contact points, resilient contact blades movable with said armature to engage said fixed contacts upon energization of said electromagnet, a latch normally in engagement with said shoulder and biased toward engagement with only one of said contact blades and toward its normal position, and condition responsive means having means for moving said latch out of its normal position in engagement with said shoulder to permit said latch to move said one contact blade away from its cooperating fixed contact.

8. In an ignition and fuel control device, the combination comprising an electromagnet, an armature positioned to be moved by said electromagnet, an abutment shoulder on said armature, fixed contact points, resilient contact blades movable with said armature to engage said fixed contacts, a slideable latch normally in engagement with said shoulder and spring biased toward and against only one of said contact blades, and condition responsive means having means for moving said latch out of engagement with said shoulder to permit said latch to move said one contact blade away from its cooperating fixed contact upon a predetermined condition arising.

9. In an ignition and fuel control device, the combination comprising an electromagnet, an armature positioned to be moved by said electro-

magnet, an abutment shoulder on said armature, fixed contact points, resilient contact blades movable with said armature to engage said fixed contacts when said electromagnet is energized, a longitudinally slid able and laterally movable latch normally in engagement with said shoulder and spring biased toward one of said contact blades and into alignment with said shoulder, and condition responsive means having means for moving said latch laterally out of engagement with said shoulder to permit said latch to move said one contact blade away from its cooperating fixed contact upon a predetermined condition arising.

10. In a furnace control, the combination comprising a relay actuated means carrying switches, one of said switches controlling energization of fuel feeding means and a second of said switches controlling ignition means, a latch member normally latched on said relay actuated means, said latch member having an abutment thereon for engagement with the ignition controlling switch and being movable with said switches in a switch closing direction and being unlatchable from said relay actuated means for movement to a switch opening position, and condition responsive means for moving said latch member out of actuating engagement with said relay actuated means.

11. A control device comprising a control switch operable by a slip-friction mechanism, a 30 safety switch operable to its open position upon the occurrence of a predetermined condition, and means operably connected to both of said switches for substantially simultaneous actuation thereof by a single movement of said means.

12. A control device comprising a condition responsive slip-friction mechanism operably connected to a control switch, a relay actuated

switch, a condition responsive switch in series with the relay of said relay actuated switch, means operable by said slip-friction mechanism to open said relay actuated switch, and means 5 associated with said slip-friction mechanism and said condition responsive switch for causing substantially simultaneous actuation thereof.

13. In a control device having a relay, a safety switch controlling said relay and a switch operated by a slip-friction mechanism for controlling said safety switch, the improvement comprising a manually operable lever pivoted adjacent said safety switch for resetting said safety switch, a cam on said lever, a second lever having a cam surface and pivoted so as to be actuated by said cam moving over said cam surface during the safety switch resetting movement of said manually operable lever, and means on said second lever for operably engaging said slip-friction mechanism.
